UNITED STATES PATENT OFFICE

1,992,088

LOCOMOTIVE TENDER AND STOKER
MECHANISMGuy M. Myers, Clarendon, Va., assignor to The
Standard Stoker Company, Incorporated, a
corporation of Delaware

Application July 22, 1931, Serial No. 552,334

3 Claims. (Cl. 105—232)

My invention relates generally to appliances for mechanically advancing fuel from a source of fuel supply to the firing opening of a steam generator. It appertains especially to such appliances for steam locomotives, and its object is the provision of means in the fuel bunker of the tender arranged to maintain a supply of fuel therein adjacent the fuel gate and the provision of means positioned below said supply of fuel for advancing the same to a firing opening in the locomotive firebox. The invention contemplates that the fuel advancing mechanism shall occupy a minimum of the space on the tender that can be used to store a supply of water.

In carrying out my invention I provide a reciprocable pusher member above the fuel bunker floor exterior of the water compartment or space that can be utilized for water storage for maintaining a supply of fuel just rearward of the fuel gate above an opening in the floor controlled by a slidable plate through which opening the fuel falls into the rearward end portion of a conveyor positioned beneath the bunker floor in a small compartment at the front end of the tender wherefrom the fuel is carried forward to the firebox. This arrangement of the fuel advancing mechanism obviates the use of an extremely long fuel trough and screw conveyor extending in the water compartment or in a special compartment formed in the water space extending rearwardly on the tender the full length of the fuel bunker as has heretofore necessarily been required with large tenders; or from another point of view adoption of the invention with either small or large tenders will greatly increase their water carrying capacity eliminating one or more stops for taking on water, hence enabling faster train schedules to be made effective.

The improvements claimed are hereinafter fully set forth.

In the accompanying drawings

Figure 1 is a central vertical longitudinal section through a locomotive and tender, illustrating an application of my invention;

Figure 2 is a transverse vertical cross section on the line 2—2 of Figure 1;

Figure 3 is a fragmentary view of the front end portion of the tender of Figure 1 with portions of the fuel advancing means shown in side elevation;

Figure 4 is a fragmentary view similar to Figure 1, but illustrating a modification of the invention; and

Figure 5 is a fragmentary side elevation of Figure 4 with part of the tender in section.

On the drawings, referring now particularly to Figures 1 to 3 inclusive, which illustrate the preferred embodiment of my invention, the locomotive as a whole is indicated at 10 and its tender at 11. The locomotive is of conventional form having the usual firebox structure 12, the back-wall 13, with a firing opening therein at 14, grates 15, and a cab 16 provided with a floor or deck 17. The backhead 13 carries the forward conduit section 18 of the fuel advancing mechanism. 10 This conduit section is fixed rigidly to the back-wall with its mouth or discharge end communicating with the firing opening 14, from which opening the aforesaid section extends downwardly and rearwardly to a point beneath the cab 15 deck 17 where it terminates in a horizontally split spherical seat portion 19. As will presently appear fuel is advanced through the conduit section 18 into the firing opening where it is received by distributing means comprising a deflecting plate 20 and the rearwardly disposed nozzle or head 21 arranged in a suitable manner to discharge a blast of pressure fluid across the deflecting plate.

The tender 11 is of improved construction. 22 represents its water compartment and 23 the fuel 25 bunker or compartment. These compartments are separated by back and side partition plates 24 together with the tender deck or fuel compartment floor 25. This floor is centrally apertured at 26 adjacent or immediately rearward of the 30 fuel gate 27. The aperture forms a discharge opening for the fuel and is controlled by a slid- 35 able plate 28. In practice this opening probably would not be more than thirty inches square.

Suitable means is provided in the fuel bunker above the floor 25 thereof, exterior of the water compartment 22, for advancing the fuel therein forwardly toward the fuel gate 27 and maintain- 40 ing a supply of fuel above the opening 26. For this purpose I provide a reciprocable pusher mem- 45 ber indicated as a whole at A. This device is secured through its housing member 29 by any desired fastening means to the back slope sheet 24. Pusher cross-heads 30 and 30a, coupled together by links 31 are adapted to reciprocate over a contour plate 32 which covers a portion of the back slope sheet 24 and the floor 25. Reciprocating movement is imparted to the heads by the rod 33 from a motor indicated generally at 34. The motor is controlled by the operating valve structure at 35 manually operable from the handle 36 at the front end of the tender. Since the detail construction of the pusher member A and its operating mechanism per se forms no part of my invention it will not be further de-

scribed. It is of known form in the art and best illustrated in United States Letters Patent 1,747,899, granted February 18, 1930 to Francis Hogg for Coal pusher for locomotive tenders.

5 It will be understood the pusher device A on its backward reciprocating movement acts to loosen the fuel and on its forward movement functions to advance the fuel to the front end of the tender over the opening 26. The device 10 is operated at intervals only when it becomes necessary to replenish the supply of fuel over the opening 26 with fuel from the rear part of the fuel bunker. Referring particularly to Fig. 1 it 15 will be seen that the stroke of the pusher member 30 is approximately equal to the longitudinal dimension of the opening 26 so that only so much fuel is pushed forwardly at each forward stroke of the pusher member 30 as can be accommodated by the opening 26.

20 Fuel falling through the opening 26 passes into the chute 37 dropping therethrough into the conveyor or elevator indicated generally at 38, the screw 39 thereof serving to carry the fuel forwardly to and force it through the conduit section 25 18 on the locomotive 10. The chute 37 is formed in a bracket or supporting member 40. This bracket comprises, the longitudinally extending parallel sidewalls 41, 41a, the transverse cross walls 42, and 43, the footplate 44, and the foot 30 members 45. The footplate and members 44 and 45 secure the bracket 40 to the tender frame 46 in a position at the front end of the tender beneath the opening 26 of the tender floor within a small water tight compartment 47 open at its forward 35 end. This compartment is formed by the upright walls 48, 49 and 49a together with the tender frame and floor.

In this form of my invention the chute 37 is provided with means for crushing the fuel. For 40 this purpose the wall 42 which forms the rear wall of the chute carries any suitable number of notched prongs 50 which cooperate with the vibratory crusher jaw 51. This jaw extends between the side walls 41, 41a and constitutes the 45 front wall of the chute 37. The sidewalls of the chute are formed by the inwardly and downwardly sloping extensions 52, 52a of the bracket sidewalls. The crusher jaw 51 is provided with the trunnions 53, which are journaled in suitable bearings in the bracket 40. One end of the trunnion 53 of the crusher jaw is secured to a crank arm 54 which 50 receives vibratory motion from the connecting rod 55 coupled to the large gear 56 which is driven from the pinion 57 on the cross shaft 58 suitably journaled in the bracket 40. Bevel gears 59 and 60 drive the shaft 58 from the motor 61 through intermediate gearing 62 and the drive shaft 63. Thus oscillating or vibratory motion 55 is transmitted to the crusher jaw 51 from the motor.

Continuous rotary motion is imparted from the same motor 61 to the screw conveyor 39 through the bevel gear 64 on the shaft 58, meshing with a similar gear 65 on a shaft 66 journaled in the wall 65 43 of the bracket 40, which shaft 66 is universally jointed at 67 to the hub shaft 68 of the aforesaid screw. The motor 61 and its intermediate gearing 62 is mounted on the tender frame 46 forward of the front wall of the tender and at 70 one side of the conveyor or elevator 38 a sufficient distance to permit lateral swinging movement thereof. Such movement of the conveyor is provided by reason of the pivotal mounting of its rearward hopper portion 69 at 70 on the footplate 75 44 and the universal mounting of its tubular for-

ward end portion 71 in the spherical seat 19 of the forward conduit section 18. The portion 71 is extensible with its ball member 72 in order to permit complete articulation between the parts of the fuel feed mechanism on the locomotive 5 and tender.

A modified form of the invention is shown in Figures 4 and 5. In this construction fuel maintained adjacent the fuel gate 27 by the pusher device A falls through the opening 26 of the tender 10 floor 25 in to an unobstructed chute 80 formed by walls having smooth internal surfaces and being secured to the tender floor by any suitable attachment means through the flange 82. The hopper 83 of the conveyor or elevator conduit 15 indicated generally at 84 is disposed directly beneath the chute 80 to receive the fuel therefrom. A screw 85 within the aforesaid conduit advances fuel through the same and in cooperation with the crusher 86, mounted in a hopper 83 over said 20 screw, serves to break down the oversize lump fuel. The screw 85 at its rearward end is driven from the shaft 87 associated with gearing 88 mounted in the housing 89 of the hopper, which gearing is driven by the flexibly connected ex- 25 tensible shaft 90 from the motor 61. In all other respects this modified form of the invention is the same as the form heretofore described and like parts have been given the same reference characters.

In operation of my invention referring particularly to the preferred construction, a supply of fuel is at all times maintained in the fuel bunker adjacent the fuel gate 27 over the opening 26 of the floor 25 by operation at intervals of the pusher 35 member A. Subject to regulation by the slidable plate 28, the fuel passes through the opening 26 into the chute 37 where a crusher composed of the prongs 50 and the vibratory crusher jaw 51 breaks down the lump fuel passing the same together with the finer particles of fuel downwardly in to the hopper portion 69 of the conveyor 38. The fuel from the chute drops directly on to the advancing screw 39 which carries it forwardly to the forward conduit section 18 through which 40 the screw forces the fuel in to the firing opening 14 where it is received by a distributing means comprising the deflector plate 20 and nozzle 21 acting conjointly to spread the fuel in aerial paths over the firebox grate 15. The flexible 45 mounting of the conveyor 38 at its ends permits articulation between the locomotive and tender. In the modified construction the operation is the same with the exception that the crushing of fuel takes place after the fuel has been received 50 by the conveying or elevating mechanism which carries it forwardly to the locomotive. In both embodiments of my invention it will be understood the pusher device A is operated independently of the conveying and crushing mechanism 55 mounted beneath the fuel bunker.

I claim:

1. In a locomotive tender, a fuel bin, a floor and a rear slope sheet for said bin, a fuel gate above said floor at the forward end of said bin, a relatively small water tight compartment beneath said floor at the forward end of the tender, said compartment having an open forward end and a rear wall forward of the lowermost end of said rear slope sheet, an opening in said floor extending from a point adjacent said fuel gate rearwardly to a point intermediate said fuel gate and the rear wall of said compartment, said opening providing communication between said bin and said compartment, a slidable plate movable across said 75

opening to control the passage of fuel from said bin through said opening, a reciprocable fuel advancing means disposed within said bin wholly above the floor thereof, said means having upstanding pushing surfaces, the foremost of said pushing surfaces in its foremost position being rearward of said opening a distance approximating the travel of said reciprocable fuel advancing means, the stroke of said pushing surface being approximately equal to the longitudinal dimension of said opening and a conveyor extending forwardly from said tender having its rearward end portion mounted in said compartment beneath said opening to receive fuel from said bin.

5 10 15 20 25 30 35

2. In a locomotive tender, a fuel bin, a floor and a rear slope sheet for said bin, a fuel gate above said floor at the forward end of said bin, a relatively small water tight compartment beneath said floor at the forward end of the tender, said compartment having an open forward end and a rear wall forward of the lowermost end of said rear slope sheet, a water reservoir extending forwardly from the rear of the tender beneath the bin to the rear wall of said compartment and on either side of said compartment, an opening in said floor extending from a point adjacent said fuel gate rearwardly to a point intermediate said fuel gate and the rear wall of said compartment, said opening providing communication between said bin and said compartment, a slideable plate movable across said opening to control the passage of fuel from said bin through said opening, a reciprocable fuel advancing means disposed within said bin wholly above the floor thereof, said means having upstanding pushing surfaces,

said pushing surfaces having a stroke approximately equal to the longitudinal dimension of said opening and a conveyor extending forwardly from said tender having its rearward end portion mounted in said compartment beneath said opening to receive fuel from said bin.

5 10 15 20 25 30 35

3. In a locomotive tender, a fuel bin, a floor and a rear slope sheet for said bin, a fuel gate above said floor at the forward end of said bin, a relatively small water tight compartment beneath said floor at the forward end of the tender, said compartment having an open forward end and a rear wall forward of the lowermost end of said rear slope sheet, an opening in said floor extending from a point adjacent said fuel gate rearwardly to a point intermediate said fuel gate and the rear wall of said compartment, a chute extending downwardly in said compartment from said opening, fuel crushing means formed with said chute, a slideable plate movable across said opening to control the passage of fuel from said bin to said chute, a reciprocable fuel advancing means disposed within said bin wholly above the floor thereof, said means having upstanding pushing surfaces, the foremost of said pushing surfaces in its foremost position being rearward of said opening a distance approximating the travel of said reciprocable fuel advancing means, the stroke of said pushing surface being approximately equal to the longitudinal dimension of said opening and a conveyor extending forwardly from said tender having its rearward end portion mounted in said compartment beneath said opening to receive fuel from said bin.

GUY M. MYERS. 35
